(57) **CLAIM**

The ornamental design for an equipment for control of electric power, as shown and described.

DESCRIPTION

FIG. 1 is a front elevational view of a first embodiment of an equipment for control of electric power, showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a top, front and right-side perspective view thereof;

FIG. 8 is a front elevational view of a second embodiment of an equipment for control of electric power, showing our new design;

FIG. 9 is a rear elevational view thereof;

FIG. 10 is a top plan view thereof;

FIG. 11 is a bottom plan view thereof;

FIG. 12 is a right-side elevational view thereof;

FIG. 13 is a left-side elevational view thereof; and,

FIG. 14 is a top, front and right-side perspective view thereof.

The broken lines in the drawings depict portions of the equipment for control of electric power that form no part of the claimed design.
